UNITED STATES PATENT OFFICE

GEORGE T. JOHNSON, OF COLUMBUS, OHIO, ASSIGNOR TO THE BUCKEYE STEEL
CASTINGS COMPANY, OF COLUMBUS, OHIO

CAR-TRUCK CONSTRUCTION

Application filed December 3, 1927. Serial No. 237,466.

This invention relates to improvements in car truck constructions and more particularly to improved spring mountings, the object of the invention being to provide simple and efficient means for supporting springs indirectly by the spring plank and for supporting certain of the springs partially by the side frame and partially indirectly by the spring plank.

10 A further object is to provide a structure in which the spring plank is removably interlocked with the side frame, and in which a separate spring seat member is disposed upon the spring plank, said separate spring seat member being made with elevated spring seat portions which cooperate with parts of the side frame in supporting the outer springs of a cluster of springs, the intermediate springs of such cluster of springs being supported 20 at a lower level upon the separate spring seat member.

With these and other objects in view, the invention consists in certain novel features of construction and combinations of parts as 25 hereinafter set forth and pointed out in the claims.

In the accompanying drawings:

Figure 1 is a partial side elevation of a car truck side frame showing an embodiment 30 of my invention;

Figure 2 is a view in section on the line 2—2 of Figure 1, the springs being indicated in dotted lines;

Figure 3 is a view partly in section and 35 partly in elevation showing a modified construction;

Figure 4 is a horizontal sectional view of the construction shown in Figure 3, and

Figure 5 is a sectional view taken at right 40 angles to Figure 3.

A portion of a truck side frame is shown in the drawing and comprises a top or compression member 1, a bottom or tension member 2, and columns 3 connecting the top and bottom 45 members and defining an opening 4 which receives a bolster 4^a. In the lower portion of the opening 4, shelves 5 to provide spring seats are formed on the lower member of the side frame. A spring plank 6 enters the lower portion of the opening 4 and rests upon the

intermediate portion 7 of the lower member of the side frame, and between the shelves 5, straight flanges 8 projecting upwardly from the side edges of said spring plank being disposed parallel with the inner walls of the shelves 5. In the present instance, the spring plank is preferably constructed of pressed sheet steel and it has detachable interlocking connection with the side frame which will be operable normally to prevent lateral displacement of the side frame but which will permit easy disconnection of the side frame from the spring plank when it is desired to remove said side frame. To effect detachable interlocking connection between the spring plank and side frame, the intermediate portion 7 of the latter may be provided with studs 9 which rise from the bottoms of recesses 10 in the top of the portion 7 of the side frame and pass through suitable holes 55 in the spring plank. The studs 9 project above the upper face of the spring plank and pass through suitable holes in a separate spring seat member 11 disposed upon the spring plank and prevent displacement of 60 said spring seat members. The separate spring seat member may consist of a pressing or a casting and is provided at diametrically opposite positions with upstanding flanges 12 provided at their upper edges with laterally 65 projecting shelves 13 which terminate in proximity to the straight flanges 8 of the spring plank and the upper faces of said shelves are in the same horizontal plane as that of the upper faces of the shelves 5 on the side frame. In order to brace the shelves 13 and flanges 12 on the seat member 11, webs 70 75 80 85 90 95 100

14 may be employed. Springs 15 are disposed under the bolster and are seated at their lower ends upon the separate spring seat member 11 on the spring plank 6. Outer springs 16 of the cluster of springs employed, are seated partially upon the shelves 5 in the side frame and partially on the elevated shelves 13 at the sides of the 95 separate seat member 11 on the spring plank, the upper ends of these springs engaging under the bolster. If desired, shims 17 may be disposed under the springs 16 and made to overlie the shelves 5 and 13.

It will be observed that a portion of the load on the outer springs 16 will be transmitted to the shelves 5 on the side frame and a portion of such load will be borne by the shelves 13 on the separate seat member 11 and as the latter is mounted upon the spring plank, such portion of the load on the springs 16 will be borne indirectly by the spring plank.

10 In the embodiment of the invention shown in Figures 3, 4 and 5, a separate spring seat member 18 is mounted upon the spring plank 6, the latter being removably interlocked with the side frame and the member 18 being connected with spring plank by the lugs 9, as previously described in connection with the form of the invention shown in Figures 1 and 2. In the construction shown in Figures 3, 4 and 5, the seat member 18 is provided with 15 upstanding flanges 19 and shelves which extend over adjacent portions of the straight flanges 8 of the spring plank and overlie the shelves 5 on the side frame. The shelves 20 and flanges 19 may be braced by webs 21.

20 Having fully described my invention what I claim as new and desire to secure by Letters-Patent, is:—

1. The combination with a side frame, of a two-level spring bearing member having indirect removable interlocking connection by 25 means of a lug and aperture joint with the side frame in its normal position and adapted when disconnected from such lugs, to permit lateral withdrawal of the side frame at the lower portion thereof and a spring plank extending between the side frame and spring bearing member.

2. The combination with a side frame and a spring plank, a separate spring seat member mounted upon the spring plank and having elevated shelves, springs partially supported by said shelves, and means on the side frame also partially supporting said springs.

3. The combination with a side frame and a spring plank having removable interlocking connection therewith, a separate spring seat member mounted upon the spring plank and having elevated shelves, springs partially supported by said shelves, and means on the side frame also partially supporting said springs.

4. The combination with a side frame having shelves, of a separate spring seat member supported upon the spring plank, said seat member having elevated shelves in the same plane as that of the shelves on the side frame, springs seated on said separate seat member between the elevated shelves thereon, and other springs supported partially by said elevated shelves of the seat member and partially by the shelves on the side frame.

5. The combination with a side frame having shelves, of a spring plank, a separate spring seat member supported upon the 65 spring plank, said spring seat member hav-

ing elevated shelves at its sides projecting over the shelves on the side frame, the spring plank and the separate spring seat member having a common removable interlocking connection with the side frame formed by a lug and aperture joint, springs supported on the spring seat member between the shelves, and other springs resting on the shelves.

6. The combination with a side frame, of a two-level spring bearing member having indirect removable interlocking connection with the side frame in its normal position and adapted when disconnected from such interlocking connection, to permit lateral withdrawal of the side frame at the lower portion thereof, and a spring plank extending between the side frame and spring bearing member, said interlocking connection being formed by lugs projecting from the side frame through apertures in the spring bearing member and spring plank.

In testimony whereof, I have signed this specification.

GEORGE T. JOHNSON.
